(57) **CLAIM**

The ornamental design for a golf cap, as shown and described.

DESCRIPTION

FIG. 1 is a perspective view of a golf cap according to my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof; and,

FIG. 8 is a perspective view of the golf cap of FIGS. 1–7 in which the free corners of the neck shade are attached by hook-and loop fasteners to the back surface thereof.

In FIGS. 1–8, the light grey texture shown on the rectangular shape on the rear upper surface of the neck shade, as well as the two under-surfaces of the visor, illustrates the hook-and-loop fastening material. The darker grey texture on the interior surface and lower outer surface of the neck shade illustrate a netted material.

The broken lines shown on the top edge of the neck shades, as well as along the rolled hem and on either side of the central seam represent stitching and form no part of the claimed design.
